UNITED STATES PATENT OFFICE.

PHELPS BROWN AND IRA E. HENDRICKSON, OF SPRINGFIELD, MASSACHUSETTS, ASSIGNEES TO WICO ELECTRIC COMPANY, OF SPRINGFIELD, MASSACHUSETTS, A CORPORATION OF MASSACHUSETTS.

TRIP FINGER FOR MAGNETOS.

Application filed December 28, 1922. Serial No. 809,406.

To all whom it may concern:

Be it known that we, PHELPS BROWN and IRA E. HENDRICKSON, citizens of the United States, residing at Springfield, in the county of Hampden and State of Massachusetts, have invented new and useful Improvements in Trip Fingers for Magnetos, of which the following is a specification.

This invention relates to improvements in trip fingers, such, for example, as those used for actuating magnetos from the reciprocating push rod of an engine, and is more particularly concerned with trip fingers which are adjustable for the purpose 10 of varying the time of actuation of the magneto relatively to the engine.

While the invention, as to certain features, is capable of general use as an adjustable trip finger, it is especially desirable 20 as a trip finger for magnetos of the type disclosed in the pending application for U. S. Letters Patent of Ira E. Hendrickson, Serial No. 504,334, filed September 30, 1921. In magnetos of this type, there is associated 25 with the trip finger a drive spring, which functions to move the armature rapidly away from its poles after the magnetic hold, or other forces tending to hold the armature to its poles, have been overcome. The trip finger proper is mounted for sliding 30 movement in its body and, when first engaging with the armature or connected parts, slides in the body without moving the armature, which sliding movement is made use of to stress the drive spring to the 35 desired degree for subsequent action. Eventually the sliding movement of the trip finger is arrested by an abutment on the body and the armature is then initially dislodged by an inelastic transmission of force 40 from the engine push rod, after which the drive spring comes into play and moves the dislodged armature away from its poles at a speed greater than that of the push rod.

This invention has for its object to provide a trip finger for the uses above described, which is of generally simplified and improved construction and capable of being manufactured at comparatively low cost.

Another object of the invention is to provide in a trip finger of the class described improved means for adjusting the latter for timing purposes.

Another object of the invention is to pro-

vide improved means for mounting the trip finger proper in its body so that it can be conveniently assembled or subsequently removed quickly and replaced in a new position to bring new wearing surfaces into play.

Other objects and advantages will appear in the following description and in the illustrative embodiment of the invention in the accompanying drawings, in which,

Fig. 1 is a small scale side elevational view illustrative of the mounting of the trip finger on an engine and the manner in which the trip finger cooperates with the magneto to actuate the latter;

Fig. 2 is a plan view of the trip finger showing the timing lever in one position;

Fig. 3 is a side elevational view of the trip finger showing the timing lever in another position;

Fig. 4 is a cross sectional view taken on the line 4—4 of Fig. 3; and

Fig. 5 is a sectional elevational view taken on the line 5—5 of Fig. 2.

Referring to these drawings;—the trip finger proper consists of a member 6, which is mounted for longitudinal sliding movement in a suitable body, such as 7. The body 7 is provided at one end with a hub 8 having an axial bore 9 to permit it to be pivotally or otherwise suitably connected to the push rod of the engine, as will later appear,—such hub and bore having their common axis disposed substantially transversely with respect to the direction of sliding movement of the trip finger 6. The body 7 is furthermore provided with an arm 10 which extends radially from hub 8 and is provided with two laterally extending portions 11 and 12, arranged in longitudinally spaced relation and forming guides for the trip finger 6.

The latter, as shown, is made up of two parts, the forward, or magneto engaging, portion 13 being of polygonal and preferably square cross section. The other part consists of a stud 14 threaded into one end of the part 13 and having at a distance from such end a head 15, preferably of cylindrical form. The magneto drive spring, heretofore alluded to, consists of a coil spring 16 which encompasses the body portion of stud 14 and acts between two washers 17 and 18. The washers 17 and 18 are loosely

mounted on the body portion of stud 14 and the former bears at all times against the forward end face of the guide 11 while the latter bears at all times against the inner end face of the square portion 13 of the trip finger.

10 The guide 11 has a cylindrical bore to slid-
ingly receive the head 15 of the trip finger and
fully encompass the periphery thereof at all
times during its normal sliding movement.

15 The guide 12 is milled out to form a slideway
for the squared portion 13 but this slideway
is open at its upper end and only partially
encompasses such portion, whereby the latter
is free to be removed from the body by an
upward movement, or a movement in a di-
rection laterally with respect to that in which
the trip finger slides. Consequently, by an
outward pull on the trip finger in a longi-
tudinal direction, the head 15 may be with-
drawn from the encompassing confines of
guide 11 and, when thus positioned, it can
be entirely removed from the body by mov-
ing it in a lateral direction. The spring 16,
20 being nearly fully expanded when in the
illustrated position, is readily compressed
to a sufficient degree to permit the action de-
scribed. This spring, however, preferably
exerts a slight force on the end walls of
guides 11 and 12, when it is positioned as
illustrated, in order to frictionally hold the
trip finger in position on the body. It will
thus be seen that the assembly of the trip
finger in the body or its removal therefrom
25 is a very simple matter, which can be accom-
plished quickly and with convenience. The
trip finger, having as shown, four similar
faces, can be removed, turned to present a
new working face and again replaced in a
40 very short time.

Since the trip finger is slidingly mounted
in the body, it becomes necessary to provide
an abutment, or abutments, with which it
may engage to limit its sliding movement
45 and provide for the desired inelastic trans-
mission of force from the body to the mag-
neto. Preferably, at least two abutments
are provided in order to secure proper tim-
ing of the magneto spark for normal engine
50 speeds and a retarded spark for starting or
low engine speeds. To this end the hub 8
is milled off on one side to provide a square
face 20 adjacent the inner end face of guide
11. A second abutment, in the shape of a
55 plate 21, is movably mounted on the body
and can be manually interposed between the
guide 11 and the abutment 20, when de-
sired. This plate 21 is pivotally mounted on
a screw 22 threaded into a lug 23 on the body
60 and is conveniently movable by a timing
lever 24 formed as an integral part of the
plate. A spring 25 coiled, about the shank
of screw 22, acts between the head of the lat-
ter and plate 21 to force the plate against
65 lug 23 and thus frictionally hold the latter

in position. The trip finger is properly
positioned for normal engine speeds when
its inner end abuts the plate 21 and, when
this plate is removed from the path of the
trip finger and the latter is allowed to en-
gage the abutment 20, retarded timing is ef-
fected. Ordinarily, therefore the plate 21
70 remains in interposed position except for
short intervals when the engine is being
started.

75 As illustrated in Fig. 5, there is a consider-
able space between the head 15 and plate 21
or abutment 20, which space is purposely
provided to permit the spring 16 to be sub-
stantially compressed prior to the dislodg-
80 ment of the armature which is effected by
an inelastic transmission of force, occurring
when this head abuts the plate or the abut-
ment. This clearance space, while desirable
85 for the reason outlined and preferred for
magneton of the type heretofore alluded to,
is not necessarily essential for all purposes
and might be nearly entirely eliminated
where the spring 16 is not required to func-
90 tion as a driving spring for the only clear-
ance then necessary would be sufficient to
allow the plate 21 to be interposed between
head 15 and abutment 20, when desired.
The trip finger has considerable utility when
95 used in this manner and the invention in
some of its aspects is to be understood to be
independent of whether or not the stressing
of the spring 16 for a subsequent armature
driving function is utilized.

100 For the special use illustrated, the spring 16
is made stronger than would otherwise be
necessary and the trip finger is allowed to
slide sufficiently to substantially fully com-
press or stress the spring.

One way of utilizing the trip finger is 105
illustrated in Fig. 1, wherein E is an inter-
nal combustion engine of any suitable type
and M a magneto of the type disclosed in the
pending application above referred to. The
armature of the magneto is mounted to slide 110
vertically and associated therewith are means
which yieldingly hold the armature in the
illustrated position and which automatically
restore the armature after it has been moved
downwardly from such position. This 115
downward movement is effected by the trip
finger, the forward upper edge of which is
arranged to engage one arm of a bell crank
lever 7, the other arm of which is attached
120 to the armature. The trip finger is connect-
ed to the the push rod r of the engine, pref-
erably by pivotally connecting the body of
the finger to a bracket such as b, which is se-
cured to the push rod. A small spring s, 125
applied between the bracket b and the arm
portion 10 of the trip finger body, or more
properly a spring seat portion 26 provided
thereon, yieldingly holds the trip finger in
the proper position to engage the bell crank
lever 7.

In operation, as the push rod *r* moves to the left the forward end of the trip finger eventually engages lever *l* but the forces, which hold the armature *a* in the illustrated position, are so strong that the armature is not immediately moved. Instead the finger slides in its body and compresses spring 16. The latter, even when fully stressed, is not sufficiently powerful to dislodge the armature, which operation is effected only when the finger engages either of the abutments provided on the trip finger body and then by an inelastic transmission of force from the push rod *r*. Immediately the armature *a* is dislodged and even a very small air gap created between the armature and its poles, the armature supporting forces, which include the force of magnetic attraction, are so materially diminished by the weakening of the latter force that the force of the stressed drive spring 16 is superior to them. The drive spring accordingly relieves its stress and moves the armature away from its poles at a speed greater than that of push rod *r*. As the latter continues to move the trip finger is freed from the lever *l*, as by a screw *t*, which, as the lever *l*, turns, pushes the finger away from the lever, allowing the finger to move to the left beyond the illustrated position.

An important feature of the trip finger consists in the means employed for varying the time of actuation of the magneto relatively to the engine. Particularly, the separation of such means from the pivotal connection is deemed desirable. Heretofore, an eccentric has been used for this purpose, such eccentric being received in a cylindrical bore of the trip finger body and forming the pivotal connection therefor. With a trip finger like the present one a substantial portion, or portions, of the eccentric surface would have to be used for abutment by the trip finger and consequently such portions would reduce the bearing surface available for the pivotal connection, especially where the eccentric is flattened somewhat on opposite sides, as is customary, to provide flat faces for abutment with the trip finger. Also the present arrangement is far cheaper to manufacture and is fully as satisfactory and efficient as the eccentric. The particular manner of assembling the driving spring on the trip finger is also considered important as well as the arrangement whereby these assembled parts may be removed from or replaced in the trip finger body quickly and conveniently. The invention has been disclosed herein, in an embodiment at present preferred, for illustrative purposes but the scope of the invention is defined by the appended claims rather than by the foregoing description.

What we claim is:

1. A device of the class described, com-

prising a suitable body and a trip finger, the latter being mounted in the former for longitudinal sliding movement, and two longitudinally spaced guides provided on the body to receive the finger, one of said guides fully encompassing one end of the finger, the other guide partially encompassing the finger at a distance from the first guide and permitting the finger to be disengaged therefrom in a lateral direction after it has been withdrawn from the first guide in a longitudinal direction.

2. A device of the class described, comprising a suitable body and a trip finger, the latter being mounted in the former for longitudinal sliding movement, two longitudinally spaced guides provided on the body to receive the finger, one of said guides fully encompassing one end of the finger, the other guide partially encompassing the finger at a distance from the first guide and permitting the finger to be disengaged therefrom in a lateral direction after it has been withdrawn from the first guide in a longitudinal direction, and yieldable means tending to hold said finger against removal from its guides.

3. A device of the class described, comprising, a body and a trip finger, the former having at longitudinally spaced points thereon two aligned guides to slidably receive the trip finger, the latter having a part of polygonal cross section and one of said guides being shaped to conform thereto and also permit removal of said part laterally therefrom, the other of said guides fully encompassing the trip finger at a distance from said part, and means yieldingly holding the finger in said last named guide, all constructed and arranged so that the finger may be manually withdrawn from the last named guide and when freed therefrom laterally removed from the first named guide.

4. In a device of the class described, a body provided with two longitudinally spaced guides one of which consists of a cylindrical slideway and the other of a slideway having three flat sides arranged in right angular relation, a trip finger having a portion of square cross section to fit in the last named guide, a cylindrical portion to fit the first named guide and a connecting portion of less diameter than the square or cylindrical portions, washers on said connecting portions, and a spring mounted on the latter and between said washers tending to force one washer against the end face of one guide and the other washer against the adjacent end face of the other guide.

5. In a device of the class described, a body provided with two longitudinally spaced guides one of which consists of a cylindrical slideway and the other of a slideway having three flat sides arranged in right angular relation, a trip finger includ-

- ing a portion of square cross section to fit in the last named guide, a cylindrical portion to slide in the first named guide and a reduced portion connecting the square and 5 cylindrical portions; washers on said reduced portion, one adjacent said cylindrical portion and one adjacent said square portion, and a spring encompassing said reduced portion and disposed between said 10 washers and tending to force one washer against the end face of one guide and the other washer against the adjacent end face of the other guide, said reduced portion being removably connected to one of the adjacent portions.
6. A device of the class described, comprising, a body, a trip finger slidably mounted therein, an abutment provided on the body serving to limit the movement of the 20 trip finger in one direction, and a spacing member mounted on the body for movement in a direction substantially transverse to the line of movement of the trip finger and capable of being interposed between the latter and said abutment, when desired.
7. A device of the class described, comprising, a body, a trip finger slidably mounted therein, an abutment provided on the body serving to limit the movement of the 30 trip finger in one direction, a spring tending to hold said finger away from the abutment, and a spacing member mounted on the body for movement in a direction substantially transverse to the line of movement of the trip finger and capable of being interposed between the latter and said abutment, when desired.
8. A device of the class described, comprising, a body, a trip finger slidably mounted therein, an abutment provided on the body serving to limit the movement of the 35
- 40
- trip finger in one direction, a spring tending to hold said finger away from the abutment, and a spacing member mounted on the body for movement in a direction substantially transverse to the line of movement of the trip finger and capable of being interposed between the latter and said abutment, when desired.
- trip finger in one direction, a spring tending to hold said finger away from the abutment, and a spacing member mounted on the body for movement in a direction substantially transverse to the line of movement of the trip finger and capable of being interposed between the latter and said abutment, when desired.
9. A device of the class described, comprising, a body, a trip finger, guiding means on the body supporting said finger for sliding movement, an abutment provided on the body with which one end of said finger may engage, means yieldingly holding said finger away from said abutment, and a pivoted member movable between said abutment and one end of said guiding means into the path 50 of said end of the trip finger.
10. A device of the class described, comprising, a body having means at one end for attachment to the push rod of an engine or the like and an arm extending radially from said means, an abutment provided on the latter, a guide provided on said arm with one end face disposed adjacent said abutment, a trip finger slidably mounted in the body and having one end slidably received in said guide, yieldable means for holding said end of the trip finger away from said abutment, and a plate pivoted to the body and movable in the space between said end face and abutment into the path of said end of the trip finger to arrest its movement at an earlier time than it would be arrested by said abutment.

In testimony whereof we have affixed our signatures.

PHELPS BROWN.
IRA E. HENDRICKSON.

Certificate of Correction.

It is hereby certified that Letters Patent No. 1,472,546, granted October 30, 1923, upon the application of Phelps Brown and Ira E. Hendrickson, of Springfield, Massachusetts, for an improvement in "Trip Fingers for Magneto's," were erroneously issued to "Wico Electric Company," as assignee of the entire interest in said invention, whereas said Letters Patent should have been issued to the inventors, said *Phelps Brown and Ira E. Hendrickson*, said Hendrickson assignor to *Wico Electric Company, of Springfield, Massachusetts, a Corporation of Massachusetts*, as shown by the records of assignments in this office; and that the said Letters Patent should be read with this correction therein that the same may conform to the record of the case in the Patent Office.

Signed and sealed this 4th day of December, A. D., 1923.

[**SEAL.**]

KARL FENNING,
Acting Commissioner of Patents.
